(57) **CLAIM**

The ornamental design for a pencil sharpener, as shown and described.

DESCRIPTION

FIG. 1 is a front perspective view of a pencil sharpener showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The pencil opening, shavings drawer, clock and/or caddy depicted by means of broken lines have been shown for illustrative purposes only and forms no part of the claimed design.

1 Claim, 3 Drawing Sheets
